(57) **CLAIM**

The ornamental design for an electrical receptacle, as shown and described.

DESCRIPTION

FIG. 1 is a perspective view of an electrical receptacle showing my new design;

FIG. 2 is a front view thereof;

FIG. 3 is a rear view thereof;

FIG. 4 is a top view thereof, the bottom view being a mirror image thereof; and,

FIG. 5 is a side view thereof, the opposite side view being a mirror image thereof.

In the drawings, the broken lines are for the purpose of illustrating portions of the electrical receptacle that form no part of the claimed design.
